UNITED STATES PATENT OFFICE.

FREDERICK A. GARDNER, OF CATSKILL, NEW YORK, ASSIGNOR TO F. A. GARDNER & CO., OF SAME PLACE.

STEAM-ENGINE.

SPECIFICATION forming part of Letters Patent No. 368,762, dated August 23, 1887.

Application filed July 1, 1886. Serial No. 206,876. (No model.)

To all whom it may concern:-

Be it known that I, FREDERICK A. GARDNER, of Catskill, in the county of Greene and State of New York, have invented a new and useful Improvement in Steam-Engines, of which the following is a description and specification.

The object of my invention is to provide for a cheap and effective construction of the valve and valve-chest portions, and also the cylinder portion of an engine, in which the power is applied to the crank-shaft to revolve the latter and without any "dead-points," and whose working-parts, instead of being exposed, are all inclosed and protected by its case from the accumulations of dust and dirt.

In adapting my invention to practice, I use two or more cylinders placed preferably side by side, or with their axes in the same vertical line; and the first part of my invention relates particularly to the construction of the piston-cylinder, which consists of a sleeve perforated at its inner end for the passage of steam therethrough, and fixed firmly in a cavity made in the casting with a cap firmly secured in and closing the outer end of the sleeve, and a cylindrical tube firmly secured in the inner end of the sleeve with an annular steam-space between the sleeve and that part of the cylinder which is secured therein, so that steam may enter the annular steam-space surrounding the outer end of the cylinder through the sleeve, and only enter the cylinder at its outer end to force the piston inward; and it also consists of a perforated valve-case adapted to receive the larger end of the valve and fitted to a tapered hole in a valve-chest having annular ports surrounding the valve-case, a hollow cap adapted to receive the outer small end of the valve and secured firmly in the valve-chest and against the outer end of the valve-case, and a tubular valve whose inner end is of largest diameter and which is adapted to slide to and fro in the valve-case and hollow cap, with a connecting-rod for connecting the valve with the operating-eccentric on a shaft, this construction being effective in securing the valve-case firmly in position, and also in preventing wear and lost motion between the valve and its connections with the shaft, and also in giving easy

access to the valve and its case whenever it is desirable to remove them for any purpose; and I will now proceed to describe my improvement, having reference to the accompanying drawings, in which—

Figure 1 is a vertical longitudinal section of the engine at the axis of the line of cylinders, with the middle portion of the crank-shaft and cranks in section. Fig. 2 is a vertical transverse section of the same at line A of Fig. 1. Fig. 3 is a horizontal section at line B of Fig. 2, with the case of the engine shown in plan, above the cylinder, at one end.

In the drawings, 2 represents the casting or frame of the engine, which is practically a closed box or case, within the upper part of which are the cylinders 3 and the valves 6. A series of holes of suitable size are made in the upper part of the casing 2, and a screw-thread, 10, is made around on the interior surface of these holes at the upper part, and a cylindrical ring, 13, having a corresponding screw-thread around the exterior, at the upper end, is screwed firmly into each hole in the casing 2, as shown clearly in Figs. 1 and 2. I make an annular internal flange or collar at the lower end of each ring 13, and an annular external flange or collar on each cylinder at 9, with a screw-thread made on the inner surface of the collar on the ring 13, and a corresponding screw-thread made on each cylinder 3 just below the collar 9, by means of which each cylinder is screwed down to a seat in its ring 13, and a head or cap, 16, is screwed firmly into the top of each ring 13. A hole is made in the upper part of the casting or casing 2 opposite each cylinder, and the lower part of this hole is made tapered, being smallest at the lower end, and a correspondingly-tapered valve-case, 5, having perforations or holes 26 around in its lower portion, and also perforations or openings 28 all around in its upper part, is fitted into this tapered hole in the casting, the inner diameter of this valve-case 5 being the same its entire length.

A steam-chamber, 27, is made the whole length of the steam-valve chest, and extends around the perforations or ports 28 in each valve-case 5, so that steam admitted into this chamber 27 may pass in through the ports 28

in each and all the cases 5. A hollow cap, 4, closed at its upper end and of uniform inside diameter, is screwed into the hole made in the upper part of the casting, opposite each cylinder, and down firmly upon the top of the tapered valve-case 5, fixing the latter firmly in place in its seat, and the inside diameter of this hollow cap 4 is a little less than the inside diameter of the valve-case 5 below it, as will 5 clearly be seen in Fig. 2. A chamber, 12, is made all around in the casting below the chamber 27, and communicates, through the perforations or ports 23, made through the lower portion of the ring 13, with the port or steam-space 18, extending around the top of the cylinder and above the piston opposite each valve, as shown clearly in Fig. 2 and in dotted lines in Fig. 3, and a chamber, 25, made in the casting partially around the ring 13 and 10 opposite the perforations or ports 23, serves as a reservoir, into which any condensation within the steam-space 18 may collect, and be drawn thence by the valve 37 through the passage 38, valve-chamber, and passage 39 into 15 the exhaust-space below the cylinders.

The valve 6 is cylindrical in its general form, with an annular projection, 8, at its upper part, made of a diameter to approximately fit the bore of the hollow cap 4, and this projection 20 may have an annular groove therein to contain a spring packing-ring, 29, or any other desirable and suitable packing which shall cause the upper part of the valve 6 to fit the bore of the hollow cap 4 properly and prevent live steam from passing up into the upper part 25 of the hollow cap 4, and the lower part of the valve 6 is provided with a similar flange or annular projection, 8, larger in outside diameter than the upper one, to fit approximately 30 the larger bore of the valve-case 5, and also similarly grooved to receive a suitable packing, 29, to fit snugly the bore of the valve-case 5. As thus constructed, the valve is smaller in outside diameter in its middle portion than 35 at the end portions, forming an annular movable chamber, 43, around the valve. I make this valve 6 tubular, as shown clearly in Fig. 2, so that should there be any accidental leakage of live steam past the upper packing of the 40 valve and into the space in the hollow-cap 4, above the valve, it may readily find its way into the exhaust-space below the valve. By this tubular construction of the valve, steam is free to pass entirely through the valve, and 45 thereby prevent any undue or excessive pressure endwise upon the valve, which might otherwise result from a leakage of live steam past the outermost packing of the valve and accumulating in the chamber within the cap at the 50 outer end of the valve.

Each piston 17 is grooved around its upper end to receive a spring packing-ring or any other suitable packing, and I make a boss, 19, on the lower side of the piston-head, with a 55 screw-thread around its exterior and a recess in its lower side to receive a portion of a ball,

20, into which is screwed the connecting-rod 21, and a cap, 22, recessed to receive the lower portion of the ball 20, is screwed onto the boss below or outside the ball, which secures 70 the rod 21 to the piston by a ball-and-socket joint. The crank-shaft 31 extends through the case 2, and the cranks 30, (to which the connecting-rods 21 are connected by any well-known means,) are arranged on the shaft at 75 an angle of one hundred and twenty degrees to each other when three cylinders are used.

A toothed or gear wheel, 32, shown in Fig. 1 and also in dotted lines in Fig. 2, is keyed to the driving or crank shaft, and a similar 80 toothed wheel (whose teeth engage with those of the wheel on the driving-shaft) is keyed to the eccentric shaft 34, which is arranged to revolve in suitable bearings and within the case, so that the eccentric shaft is made to 85 revolve at the same speed and therefore always with the same relative position to the crank-shaft.

There are three eccentrics, 33, one for each crank and piston, and they are secured to the 90 eccentric shaft at an angle of one hundred and twenty degrees to each other and corresponding to the relative positions of the cranks with each other on the crank-shaft; and each valve 95 6 is connected with its eccentric by any ordinary arrangement of eccentric rod and band, 35.

A steam-inlet is made at any convenient point to admit live steam into the chamber 27, and an orifice is made at any convenient point 100 in the case 2 below the valve to conduct away the exhaust-steam, both having suitable pipes connected therewith.

Suppose the piston 17 in one cylinder and its corresponding valve, 6, to be in the position shown in Fig. 2: If live steam be admitted into the chamber 27, it will pass through the ports 28 into the chambered portion 43 of the valve 6, and the lower flange or projection, 8, on the valve being the largest, the 110 preponderance of steam-pressure will be downward against the valve to always hold the eccentric against the shaft. As soon as the upper edge of the lower flange, 8, in the downward movement of the valve passes below 115 the upper edge of the lower ports, 26, in the valve-case 5, the steam will pass down through these ports 26 into the port 12, and thence through the ports 23 into the steam-space 18, around the upper end of the cylinder and above the piston, which will be forced down thereby, to apply power in revolving the crank-shaft and completing the downward stroke of the piston. As soon as the lower edge of the lower flange, 8, of the 120 valve 6 passes above the lower edge of the ports 26 in the upward movement of the valve the exhaust-steam from the space above the piston 17 is free to pass out through the ports 23, 12, and 26 into the exhaust-space below 125 the valve, whence it is conducted off through the exhaust-pipe.

Each cylinder-piston and its valve operates in precisely the same manner, but all in rapid succession, when the engine is in operation.

It will be seen that live-steam pressure is only applied to the upper side of the piston, while the other side is only exposed to the exhaust-steam in the exhaust-space, and that the pistons exert their power against the crank-shaft in rapid succession, and only in one direction to revolve the shaft either way, whether in one direction or the other, the pressure against the crank-shaft during the opposite or upward movement of the piston being simply the weight of the latter and its rod.

15 The pressure of the valves against the eccentric-shaft and the pressure of the pistons against the crank-shafts are both always in the same direction, and consequently there is little or no noise in the running of the engine, 20 and the wear of both shafts is reduced to a minimum.

If steam should condense in the steam-space 18 around the cylinder, the condensation will collect in the space 25, and by turning the 25 valve 37 away from its seat the water will run down through the passages 38 and 39 into the exhaust-space below and be drawn off by a suitable cock placed for that purpose.

Supports 45 may be cast with the frame or 30 casing 2 to give a firm bearing to the crank-shaft 31 near the cranks, and stuffing-boxes 46 arranged in each end of the casing and around the crank-shaft to prevent the leakage of exhaust-steam through the case and around the 35 shaft.

Any well-known automatic oiling apparatus may be attached to the working parts within the casing in the exhaust-space for the proper lubrication of the working parts therein.

40 It will be seen that when the engine is in operation the upper steam-chamber, 27, always contains live steam and the exhaust-steam always passes out through the chamber 12 below, and thence into the steam-space below the valve, and that by making the valve 45 with its inner end of largest diameter and the valve-case and its hollow cap together of cor-

responding form, the latter of smaller inside diameter to fit the outer and smaller end of the valve, the valve always remains under a pressure of live steam in the same direction. 50 This is a very important feature in causing a reduction of wear and noise in the running of an engine. It will be perceived that to cast the main casting 2 the sleeve or ring 13, closed 55 at its outer end, and the tube 3, open at both ends, all in one piece, and with the steam-space 18 around the upper end of the cylinder-tube 17 and above the open end of the latter, would be very expensive, and would be 60 attended with many difficulties; and I consider this construction an important feature of my invention in a saving of labor and expense.

Having thus described my invention, what I claim as new is—

1. The combination, in an engine, of a valve-chest provided with a tapered hole and annular steam spaces or ports surrounding and communicating therewith, a perforated tapered valve-case fitted into said tapered hole, 70 a hollow valve-cap adapted to receive the small outer end of the valve, and secured firmly in the valve-chest and against the outer end of the valve-case, and a cylindrical tubular slide-valve whose inner and larger end is 75 adapted to slide in the valve-case and whose outer small end is adapted and fitted to move in the hollow valve-cap, and a connecting-rod for connecting the valve with the operating-eccentric on the eccentric-shaft, substantially 80 as described.

2. The combination, in an engine, of the perforated cylinder-sleeve 13, closed at its outer end and secured firmly in the casting, and the cylinder 3, open at both ends and secured in the inner end of the sleeve, with an annular steam-space extending around between the sleeve and that portion of the cylinder enclosed within the sleeve, substantially as described.
